UNITED STATES PATENT OFFICE.

JOSEPH SACHS, OF HARTFORD, CONNECTICUT, ASSIGNOR, BY MESNE ASSIGNMENTS, TO THE HART & HEGEMAN MANUFACTURING COMPANY, OF HARTFORD, CONNECTICUT, A CORPORATION OF CONNECTICUT.

LOCK FOR INCANDESCENT-LAMP STRUCTURES AND THE LIKE.

1,217,830.

Specification of Letters Patent. Patented Feb. 27, 1917.

Application filed February 24, 1913. Serial No. 750,137.

To all whom it may concern:

Be it known that I, JOSEPH SACHS, a citizen of the United States, residing at Hartford, in the county of Hartford and State of Connecticut, have invented certain new and useful Improvements in Locks for Incandescent-Lamp Structures and the like, of which the following is a specification.

This invention relates to locks for incandescent lamp structures and the like, and it is intended to prevent the surreptitious removal of incandescent lamps from their sockets or to prevent the separation except by authorized persons, of any parts which are co-operatively usable. In the form of the invention hereinafter particularly described the locking mechanism is associated with an incandescent lamp and its socket but it can be incorporated equally well in other connections. I also employ in the organization a special form of catch ring to coact with the lamp or other part and by the use of which said lamp or the like is furnished with a substantial catch portion so that it will properly co-operate with the locking or securing means of whatever character the same may be.

In the drawings accompanying and forming part of the present specification I have represented in detail some of the numerous forms of embodiment of the invention which to enable those skilled in the art to practise the same, will be fully set forth in the following description. I do not limit myself to this disclosure; I may deviate therefrom in radical particulars within the scope of the invention defined by the claims following said description.

Referring to said drawings:

Figure 1 is a sectional elevation of an incandescent lamp and its socket provided with a lock involving my invention.

Figs. 2 and 3 are practically similar views illustrative, however, of different forms of locks.

Fig. 4 is a detail view of a latching and a locking band, the latter being in section, and both being those shown in Fig. 1.

Fig. 5 is a transverse section of the latching and locking bands shown in Fig. 2.

Fig. 6 is a view corresponding substantially with Fig. 4 of the latching and locking bands shown in Fig. 3.

Fig. 7 is a cross section on the line 7—7 of Fig. 6.

Fig. 8 is an elevation of a different form of locking band in unset or uncompressed relation.

Fig. 9 is a like view of the same compressed or set.

Fig. 10 is a top plan view of another form of locking band uncompressed or unset.

Like characters refer to like parts throughout the several views.

Lamp locking means involving my invention preferably comprise a latching band and locking or sealing band of any suitable material, such as sheet metal, brass answering satisfactorily in this connection. These two members may vary radically as to structure, although I prefer for ease of assemblage that the latching band be split or divided to facilitate its connection with either or both the lamp and its socket. While the locking or sealing band might also be split or divided I prefer that the same be continuous or unbroken. There are many ways in which these two bands can be related to each other, and there are many ways in which the latching band can be associated with the lamp and its socket; I will describe several of each. It is essential that the shells of the lamp and socket be insulated from each other, and this result can be accomplished in several ways although as will hereinafter appear, it is advantageously secured by insulating the latching band from said base shell in any one of several ways. With the foregoing general statement it will now be well to describe more in detail the several illustrated forms of the invention and in this connection reference should first be had to Figs. 1 and 4, the incandescent lamp structure being represented in the first of these two views. By "incandescent lamp structure" I refer to both the lamp and its socket and the usual accessories by which they are operatively combined.

In Fig. 1, the lamp is denoted by 2 and its socket by 3 both being of standard construction although a lamp hereinafter described, is slightly different from those most frequently seen at the present time for which purpose I have devised a catch portion of a novel construction, to co-operate therewith as will hereinafter appear.

The latching band or securing member shown in said Figs. 1 and 2 is designated by 4 and as already stated, it is preferably

split or divided. This latching band or securing member ordinarily (but not essentially) has separate catch portions which coact with catch portions on the lamp and 5 socket and these several catch portions may be of any desirable kind. The neck of the lamp 2 is shown surrounded by the ring 5 preferably but not necessarily split; by employing a split ring, it can be very easily 10 applied. This ring constitutes a suitable catch portion on the lamp while the annular bead 6 on the socket 3 presents a suitable catch portion thereon. Said ring 5 is in this particular showing preferably of insulating material, such as fiber, and when 15 in constricted relation, its inner beveled edge engages over the upper or outer edge of the base shell of the lamp so as at such time to present in effect a fixed or rigid 20 collar on the lamp, and when the lock is set, to prevent the lamp from being unscrewed. The flanges 7 and 8 extending inwardly from the latching band 4 provide convenient catch means on said band for coöperation 25 with the catch portions 5 and 6 respectively. When the latching band 4 is contracted, for instance by applying a locking band, its flanges 7 and 8 engage the ring 5 and bead 6 respectively. It will be apparent that if 30 this relation be maintained, the lamp cannot be taken from its socket.

To maintain the latching band 4 in lamp securing position I provide a second band as 9 which acts as a lock or sealing member 35 for the companion band, said second or locking band being interlocked with the inner band, and this interlocking condition can be obtained in many different ways. When the locking band is set or is in lock- 40 ing relation, it can only be removed by slitting or cutting entirely through it; in other words the locking band is permanently locked in place, differing in this respect from latching bands which are locked by 45 one motion and are released by reversing the locking motion. The locking band therefore must be destroyed before it can be removed. Said locking band is originally in the form of an unbroken cylinder, its inner 50 diameter being greater than the maximum external diameter of the latching band 4, which as will be observed has two external beads 10 between which the locking or sealing band is disposed when in active or lock- 55 ing position; as will be inferred the maximum diameter of the latching band is defined by these beads 10 so that the locking or sealing band can be readily slipped over the same into coincidence with the space be- 60 tween said beads. It will be assumed that the latching band 4 is in place and that the locking band in its original or cylindrical condition (preferably slightly corrugated) is around said latching band and opposite 65 the space between the two beads 10. In this

event it becomes necessary to set said locking band. This can be accomplished by circumferentially compressing said locking or sealing band, with the aid of a suitable tool, said locking band as shown being then more deeply corrugated or crimped into substantial, gripping engagement with the latching band so that before the locking band can be taken off it must be snipped entirely therethrough. This locking band might 70 originally be non-corrugated or plain provided it be of such nature as to be compressed into locked or sealed relation.

In my application for patent for anti-theft devices for incandescent lamps filed 80 August 26, 1912, Serial No. 716,959 I have shown, and described some of the features illustrated and set forth in the present case 85 not claimed herein. Among these is the latching band insulated from the lamp. As 90 will be clear the present invention resides in a locking band associated with a latching band such as that shown in said co-pending application or with any other that answers my purposes, and also in a novel 95 form of catch to coact with the lamps. The latching band 4 is applied and operates precisely like the latching band shown in my prior application; that is to say said band 4 is slightly opened so that its flanges 7 and 8 can be slipped over the ring 5 (already 100 applied) to the lamp and bead 6 respectively after which the locking or sealing band 9 is put in place in the manner already set forth.

In an incandescent lamp structure employing a lock for the lamp, it is ordinarily essential that at least one of the parts, that is either the lamp or its socket, have a catch portion engageable by a catch portion on 105 a securing member which may be either a latching band or a locking band as I have termed them. In some cases the lamp can be prevented from wrongful removal from its socket by suitable locking means, acting in 110 part in conjunction with a catch portion on the lamp. In my own case, I have provided heretofore a catch portion in the form of a ring of fiber to encircle the neck of the lamp at the junction of the shell with the 115 glass thereof. This ring finds a bearing against the inturned or inspun outer portion of the shell. A lamp base thus made presents an ample, adequate seat or shoulder for such a fibrous ring. Recently, however, 120 there has been introduced a lamp having a form of base shell without this inturned upper end and the only seat for a catch ring, meager and scant as it is, is represented merely by the thickness of said shell. To 125 meet this condition it has been necessary to devise a special form of catch ring and I prefer that the same be of metal. I prefer also that at least the inner marginal portion of this ring be thin by which I mean 130

that it is sized or that its depthwise extent or thickness of the metal shall be not greater than enough to enter the space (small it is true) between the upper edge of the base shell and the glass of the lamp. It is conceivable that the remainder of this ring need not be of such thickness. For ease in manufacture the ring may be of the same or uniform thinness throughout its entire extent or merely beveled at its inner edge. Another important requisite is that the catch ring, when employed in connection with this new type of lamp, should be springy or resilient so that it can inherently or by its own action embrace or hug the neck of the lamp immediately next the neck of the lamp at outer edge of the base shell. In applying this ring it is opened to an extent sufficient to be freely passed over the upper edge of the shell, after which the ring automatically closes upon the glass of the lamp, to such an extent as to assure its firm bearing against the shell. When the locking mechanism is freed, in the present case, by cutting through the locking band, to obtain access to this catch ring, its terminals can with the aid of a suitable tool or even directly by hand, be spread or separated, to enlarge or expand the catch ring sufficiently to effect its removal.

Referring now to Figs. 2 and 5, the lamp is designated by 12 and its socket by 13. The base shell of this lamp is unlike that shown in Fig. 1, said lamp 12 being provided with a type of catch ring as 14 hereinafter more fully set forth, primarily to conform to this kind of shell. The catch on the socket is denoted by 15, and as before consists of the customary bead present on certain existing types of standard sockets. It will be perceived on reference to Fig. 1 that the upper portion of the base shell of the lamp 2 is provided with a rounded or inturned portion which provides an ample bearing for a fibrous catch ring as 5. The shell of the lamp 12, however, has no such ample surface, the only bearing offered being defined by the thickness of the shell so that it is not possible within practicable limits to provide a fiber catch ring to coöperate therewith. To coact with this particular form of shell I provide a metal catch ring as 14, which is comparatively thin but yet strong enough to withstand the strain of a pull on any attempt to wrongfully withdraw said lamp from its socket. This ring 14 is preferably split and is passed along the base shell of said lamp 12 and over the upper edge thereof when it automatically closes into firm engagement with the neck of the lamp and fits against said upper edge.

Said ring 14 is preferably insulated from the latching band 16 and this effect can be secured in a great many different ways, for

instance by setting said metal ring 14 within the ring 17 of insulating material, said ring 17 being provided with an inwardly disposed annular flange 18 against which the metal ring 14 fits, said flange 18 in turn bearing against the catch flange 19 of said latching band 16, said latching band having a second and practically duplicate catch flange 19' to coöperate with the bead 15. The latching band 16 is applied almost exactly like and in function is a duplicate of the latching band 4; in fact the main difference in construction between the two forms of bands is that the band 4 is externally beaded while the band 16 is not. It will be clear that before the lamp 12 is inserted in its socket 13, the ring 14 is put on after which the latching band 16 will be applied. The insulating ring 17 may initially be inserted in the latching band 16 or the ring 14 can be first introduced into the ring 17, which latter may be continuous or split these points being immaterial, the essential thing in view in this particular form of lamp being to provide catch means which will act properly in conjunction with the base shell thereof and which when of metal must be so insulated as to break electrical continuity between the socket and lamp shell the ring 17 being one of several such ways. The same result could be secured by interiorly lining said band 16 with some insulating substance throughout its entire extent or only at that part thereof which comes in contact with the metal ring 14 or its equivalent.

The locking band 20 has preferably a positive or direct interlocked connection with the latching band 16, for example by a tongue or projection on one to enter a slot or opening in the other. I prefer that the tongue be upon the locking or sealing band 20 and I illustrate two of such tongues; the same being denoted by 21 and being diametrically opposite each other. Initially these tongues are outside the inner surface of said locking band 20, the inner diameter of which is a trifle larger than the external diameter of the latching band 16 which like the one already described is split or divided, and by reason of this construction, the band 20 can be slipped over the complementary band 15 although the fit is close. The seats for the locking or holding tongues 21 are made as slots in the inner band 16, means being provided to guide the locking or sealing band 20 so that the locking tongues will be positioned in proper relation to the receiving slots 22 respectively therefor. The guiding means for this purpose may vary decidedly although those shown and now to be described meet the necessary requirements. Upon the exterior of the latching band 16 is a bead or ridge 23 to enter a channel or groove 24 in the interior of the locking band, which centers the two bands or guides them

relatively in such manner that when a certain degree of said relative movement has been accomplished the tongues 21 will be brought exactly opposite their receiving slots 22 at which time said tongues will be pushed into said slots to thus lock the band 20 permanently against withdrawal. It is therefore necessary before said band 20 can be taken off that it be snipped through.

Referring now to Figs. 3, 6 and 7. The lamp shown in Fig. 3 is denoted by 25 and its socket by 26, the catch portion of said lamp being designated by 27 and consisting of a ring practically like the ring 14 already described and provided with a ring 28 of insulating material, as fiber, molded around the outer marginal portion of said ring 27 which like the ring 14 engages above the upper edge of the base shell of said lamp 25, the insulating portion or ring of said catch member 27 being directly engageable by a catch as the flange 29 on the locking band 30 which encircles the latching band 31 which in this form of the invention, together with only one of the elements of the lamp structure, viz., the socket, said band for such purpose having an in-turned annular flange or catch portion 32 to engage below the catch portion or standard bead of the socket 26. It will be evident that when I use the term incandescent lamp structure, I mean to include both the lamp and its socket. The locking or sealing band 30 in addition to serving the functions of the locking or sealing bands already described also acts as a latching band or partakes of some of the functions of the same, as in addition to locking or sealing the latching band 31 it also catches on the lamp. It will be clear that the arrangement shown in said Fig. 3 might be reversed, that is the locking and latching band might coöperate directly with the socket and the latching band with the lamp. The two bands 30 and 31 can be interlocked in various ways; for instance the latching band may have exteriorly thereof several tongues 33 automatically projectable (owing to their resiliency) into seats or recesses 34 formed in the locking band 30.

When the tongues come opposite the seats 34, the spring tongues spring of themselves into their respective seats 34, it being understood that prior to this operation the band 30 is slipped over the band 31 and the two relatively moved toward each other until the interlock between them is effected. Before the lamp 25 can be removed it will be necessary to snip through the locking and sealing band 30 and to facilitate this operation the flange 29 and body of said band may be slotted as at 35. The cutting implement will be inserted in this slot when it is necessary to sever the band 30.

In Figs. 8 and 9 is represented another form of locking band, denoted by 36. This band

is initially cylindrical and it may be used in connection with any of the latching bands already described. It will be supposed that it is to be employed in conjunction with the latching band 4. In this case, the internal diameter of the band 36 is greater than the external diameter of said latching band 4 at the beaded portions so that the said locking band 36 can be slipped over the latching band 4 and then compressively secured in locked relation. To facilitate the compression of said locking band 36, the same may have in its opposite edges the notches 37 and the elongated body slot 37'. After the band 36 has been brought coincident with the channel between the beads 10, it will be compressed in the space between said beads, its diameter being thereby reduced in consequence of which said band 36 will be constrictively or distortively interlocked with the latching band, its diameter during such procedure being reduced. In Fig. 9 the band 36 is shown in its distorted or set condition.

In Fig. 10 the locking or sealing band 38 is shown provided with an outwardly-extending lug or ear 39 integral therewith and of hollow construction of substantially U-shape in cross section. By compressing the hollow lug 39 the band 38 can be distortively interlocked with a latching band and can be removed only by destroying the same, for example by cutting entirely through said band 38.

I have thus far described a lock which when in operative relation engages directly with the parts to be locked together or held against separation. It will be clear that my invention may be also embodied in a lock serving the same purpose, in which only one of the parts to be held against separation, is directly engaged while the other part is so embraced or surrounded that it cannot be removed from the combined structure so long as the lock is intact. Said embodiment would be a lamp-guard in which the guard in whole or in part forms one of the members of my lock and is provided with a complementary member which may be the locking or sealing member and which would have to be, in order to be unlocked, destroyed to permit of the unlocking of the complete lock and the separation of the parts of the structure.

What I claim is:

1. A lamp lock comprising a securing band and a locking band, one of which incloses the other, the two bands being distortibly interlocked.
2. A lamp lock comprising a securing band and a locking band, one of which incloses the other, the two parts being distortibly interlocked which constitutes the sole means for holding them in assembled relation.
3. A lamp lock comprising a securing band

and a locking band, one of which incloses the other, the two parts being distortibly interlocked, and a split catch ring inclosed by one of the bands to insulate the same from the base shell of an incandescent lamp.

4. A lamp lock comprising a securing band, and a locking band, the securing band being located in the locking band and being split, the two bands being distortibly interlocked.

10 5. A lamp lock comprising a securing band, and a locking band inclosing the securing band, the two bands being distortibly interlocked, the securing band having a portion to engage a holding part on a lamp socket and also having a split catch ring separate therefrom.

6. A lamp lock comprising a securing band and a locking band surrounding the securing band, the two being locked together by the compression of the stock of one of them. 20

7. A lamp lock comprising a securing band and a locking band, one of which incloses the other, the two parts being distortibly interlocked, and means inclosed by one of the bands for insulating the same from the base 25 shell of an incandescent lamp.

In testimony whereof I affix my signature in presence of two witnesses.

JOSEPH SACHIS.
